UNITED STATES PATENT OFFICE.

THEODORE H. OPPENHEIM AND BERNARD SELHORST, OF COLDWATER, OHIO, ASSIGNEES TO NEW IDEA SPREADER CO., OF COLDWATER, OHIO, A CORPORATION OF OHIO.

ALIGNMENT JIG FOR USE IN CASTING ROLLS.

Application filed November 20, 1924. Serial No. 751,081.

To all whom it may concern:

Be it known that we, THEODORE H. OPPENHEIM and BERNARD SELHORST, citizens of the United States, residing at Coldwater, in the 5 county of Mercer and State of Ohio, have invented certain new and useful Improvements in Alignment Jigs for Use in Casting Rolls, of which the following is a specification.

10 This invention relates to means for casting rolls and is intended more particularly for use in casting the snapping rolls of corn-husking machines but it may be advantageously employed in the casting of all rolls 15 where it is desirable to have the spindles or shafts of the rolls in axial alignment.

It is common foundry practice at this time to place a long piece of cold rolled shafting or short pieces to form trunnions in a mold 20 and then pour the metal for forming the roll around the shafting or trunnion pieces, the shaft or trunnions being thereby integrally united with the body of the roll. In general, the shaft or trunnion member under 25 present methods is warped or slightly distorted in the casting process and it is necessary to subsequently place the roll and the shaft or trunnion in a lathe and turn it down to the desired diameter. The shaft 30 or trunnion is, therefore, originally of a greater diameter than is desired in the finished article in order to permit subsequent machining. Obviously, this process causes a waste of material and destroys the wearing 35 qualities of the shaft owing to the fact that the skin of the cold rolled shafting is broken or entirely destroyed when it is turned down in the lathe. It is the object of our present invention to provide means 40 for use in casting rolls and to so employ such means that the shafting or the trunnion piece may be placed in the mold and be originally of the proper diameter desired in the finished article, avoiding the waste 45 and the cost of subsequently turning the spindles in a lathe. It is also an object of the invention to provide means whereby the spindles or shafts will be in exact axial alignment in the finished roll and the finishing 50 of the roll in a lathe will be expedited while the original skin of the cold rolls will be retained and consequently the durability of the finished article will be enhanced. These objects, and other objects which will

incidentally appear in the course of the following description, are attained in such means as is illustrated in the accompanying drawings, and the invention resides in certain novel features which will be particularly pointed out in the claims.

In the accompanying drawings:

Figure 1 is a perspective view of our improved alignment jig;

Fig. 2 is a similar view showing the jig in position upon the following board and in the 65 drag flask;

Fig. 3 is a similar view showing the jig in position with a portion of the cope flask showing above the pattern, and

Fig. 4 is an end view of the jig.

The drawings show the invention employed in connection with a sand mold but it is to be understood that it may be employed in connection with chill molds or core molds or molds of any other type.

In carrying out our invention, we employ a rigid frame which is preferably rectangular in form and consists of end bars 1 and 2 connected at their ends by side members 3 which are preferably of angle bar formation whereby longitudinal flanges or ribs 4 are formed upon one side of the side bars at the outer ends of the same. These flanges serve to reinforce the side bars and also aid in holding the jig in place in the drag flask, as will be hereinafter set forth. At the center of each end bar 1 or 2 is formed a groove 5 which may be V-shaped, as shown in Fig. 1, or semi-cylindrical, as shown at 6 in Fig. 4. These grooves extend parallel with the side bars 3 of the jig and consequently are in axial alignment. Each end bar is reinforced on one side with a transverse rib 7 extending between the flanges 4 of the side bars, as shown clearly in Fig. 2, it being understood that the grooves are formed in flat faces of the end bars which are located in planes parallel with the inwardly projecting webs of the side bars. The flat faces of the end bars are uppermost in Fig. 1 and are adapted to rest upon the follow board 8 in the use of the device, as shown in Fig. 2. We also employ clamping bars or plates 9 which are adapted to rest upon the flat faces of the end bars 1 and 2 and are provided at their centers with grooves 10 corresponding to the mating grooves 5 or 6 in the end bars of the

jig, as shown in Figs. 1 and 4. Openings 11 are formed in the end bars to receive cap screws or bolts 12 which are inserted through openings provided therefor in the end portions of the clamping bars whereby the bars may be securely fastened upon the jig frame. Preferably, the clamping bars are reinforced at their centers by ribs 13 extending over the grooved portions thereof.

- 10 In using the device, the jig frame is placed upon the follow board 8 with the flat faces of the end bars 1 and 2 resting upon the upper face of the follow board and the grooves 5 or 6, as the case may be, extending over the 15 end portions of the pattern member 14 on the board. The drag flask 15 is then placed in position upon the follow board and packed with sand, as indicated at 16, after which the bottom board 17 is secured in place by the clamps 18, the formation of the flask and the sand mold being accomplished in the usual manner. The flask is then inverted and the follow board removed, after which the cope flask 18' is placed in 20 position and packed with sand, as indicated at 19, in the usual manner so as to complete the mold. Before placing the cope flask in position and forming the upper half of the mold, we place core pieces 20 in the grooves 25 5 or 6 of the jig and then secure the clamping bars or cap plates 9 in position over these core members, and it is to be noted that these core members are provided with annular flanges or disk portions 21 which 30 will leave a shouldered recess in the sand of the mold. After the cope has been fully packed with sand, it is lifted off the mold and the pattern removed, the clamping bars or cap plates 9 being also removed so as to 35 permit the core pieces 20 to be withdrawn. The shaft members are then placed in the 40 grooves of the jig and the cap plates again secured in place, core rings similar to the disks 21 being fitted about the shafts against the ends of the extended portions 22 of the 45 end bars and cap plates of the jig, after which the cope flask is secured in place and the pouring performed in the usual manner.
- 50 In securing the cap plates or clamping bars 9 in position over the ends of the shafting or trunnion members, the walls of the grooves within the end members of the jig and the said cap plates or clamping bars will be caused to engage the said shaft or 55 trunnion members so that they will be held firmly in axial alignment, but the parts are so proportioned that, while the shaft or trunnion members cannot move laterally and are, therefore, prevented from bending or 60 warping, they can slip longitudinally sufficiently to accommodate the expansion and contraction which takes place as a result of the variations of temperature in the mold and the pouring during the casting operation. The side and end members of the jig 65

will be firmly embedded in the sand and they will be far enough from the heated mass so that they will not expand or warp while in use. By using this jig, we are able to employ a shaft member which is of the exact diameter desired in the finished article and there will be no waste due to subsequent turning in a lathe. Moreover, if it should be necessary to grind the rolls or otherwise finish them after the casting operation has been completed, the spindles or trunnions are simply placed on centers in a lathe and a cutting tool can then be run the entire length of the roll or if it is not desired to turn the roll in a lathe, the roll with its spindle may be placed on centers and the contour of the rolls may be ground. The use of our jig retains the original skin on the cold rolls and the shafting studs or trunnions at the ends of the roll are in perfect axial alignment. The end core members which are placed around the trunnion or shaft members and against the ends of the jig tend to protect the adjacent portions of the jig from the heat so that it will not warp and it, furthermore, counteracts the chilling effect of the steel stud or shaft and prevents the formation of chilled cast iron where the metal might run out. Our improved jig is very simple in construction, may be produced at a low cost and may be employed in any mold and effect a reduction in the cost of production as well as producing a superior article.

Having thus described the invention, we 100 claim:

1. The combination with a mold for casting rolls having shaft members at their ends, of means for securing shaft members at the ends of the mold cavity and maintaining said members in axial alignment while permitting endwise movement of the same during contraction of the cast roll.

2. A jig for use in casting rolls with shaft members in their ends comprising an open frame adapted to fit within but free of the mold around the mold cavity and in spaced relation to the cavity and provided at its ends with means for securing shaft members in axial alignment projecting into the ends of the mold cavity while permitting endwise movement of the shaft members, and core members adapted to rest against the end portions of the frame around the shaft members held therein.

3. A jig for use in casting rolls having shaft members in their ends comprising an open frame adapted to fit within but free of a mold and provided at the centers of its ends with grooves extending longitudinally and in axial alignment, and similarly grooved clamping members adapted to be secured upon the end portions of said frame whereby to secure shaft members in axial alignment and restrain sidewise movement

of said members but permit endwise movement thereof.

4. A jig for use in casting rolls having shaft members in their ends comprising a rectangular frame adapted to fit within but free of the mold, the end members of which frame have flat upper faces and longitudinally extending grooves in the flat faces of said end members at the centers of the same, and clamping bars adapted to be secured upon the flat faces of the end members and provided with grooves to mate with the grooves in said members, the end members and the clamping bars having central portions projecting inwardly to the respective ends of the mold cavity to support shaft members against sidewise movement while permitting endwise movement thereof.

5. A jig for use in casting rolls having shafts in their ends consisting of a rectangular frame having longitudinally extending ribs along the outer edges of its side

members and provided with transverse ribs on its end members extending between the said ribs on its side members, the end members having flat faces at the sides remote from the ribs on said members and being provided in said flat faces at their centers with longitudinally extending grooves, and clamping plates adapted to be secured upon the flat faces of the end members and provided with flat faces to form contact with the flat faces of the end members and having grooves mating with the grooves in the end members whereby to secure shaft members against sidewise movement while permitting endwise movement thereof, said clamping plates being provided on their outer faces with ribs extending transversely of the mold.

In testimony whereof we affix our signatures.

THEODORE H. OPPENHEIM. [L. S.]
BERNARD SELHORST. [L. S.]
